UNITED STATES PATENT OFFICE.

EDGAR C. GEORGE, OF NORWOOD, OHIO, ASSIGNOR TO ALLIS-CHALMERS MANUFACTURING COMPANY, OF MILWAUKEE, WISCONSIN, A CORPORATION OF DELAWARE.

CORE CONSTRUCTION FOR ELECTRICAL APPARATUS.

1,282,684.

Specification of Letters Patent.

Patented Oct. 22, 1918.

Application filed February 19, 1917. Serial No. 150,268.

To all whom it may concern:

Be it known that I, EDGAR C. GEORGE, a citizen of the United States, residing at Norwood, in the county of Hamilton and State of Ohio, have invented a certain new and useful Improvement in Core Construction for Electrical Apparatus, of which the following is a specification.

This invention relates in general to electrical apparatus, and has particular relation to means for promoting efficient ventilation of the cores of such apparatus while maintaining a mechanically strong and durable core construction.

The present invention is of particular utility in a core construction of a type wherein sections of the core, usually made up of laminations, are spaced apart and held in such spaced relation as to provide one or more passageways through which air is circulated in the operation of the apparatus to assist in maintaining the core and windings associated therewith in a cool operating condition, and wherein the spacing means used are in the form of a plurality of separate spacing elements secured to one of the core sections, as by welding to the end lamination of the section, and bearing against the other core section. With a construction of this character, it may be possible that an individual one of the spacing elements may, because of some imperfection in the union between the spacing device and the end lamination, become detached from the lamination and drop out of operative position, or be thrown, in the case of a rotor core, into the air-gap of the apparatus while the latter is in operation.

In accordance with the present invention, means are provided for locking a plurality of the individual spacing elements together and in operative position relative to the core sections which they serve to space apart, the general construction serving to prevent an individual spacing device from being forced out of operative position, or, in the case of a dynamo-electric machine, from dropping or being thrown into the air-gap of the machine during the operation thereof, should such spacing device become detached from the core section by reason of any imperfection in the attachment of the device to the core section. These locking strips are attached to the core section, either directly or through one or more of the spacing devices,

and each of a group of spacing devices is so associated with a locking strip that it is impossible for any individual spacing device to be dislodged from operative position unless all the spacing devices are so dislodged and the locking strip itself is detached from the core section. The general construction is such as provides for the required mechanical strength and ventilating space while fully insuring against damage due to accidental detachment of an individual spacing device, the desired results being secured with minimum weight of material and cost.

It is an object of this invention to provide improved means comprising a plurality of individual spacing elements for spacing the sections of electrical apparatus, which means may be readily and cheaply provided and assembled, and which provides for the required mechanical strength and the efficient ventilation of the core while insuring the retention of the individual spacing elements in operative position.

It is a further and more specific object of this invention to provide improved means for spacing apart sections of the core of electrical apparatus, this means involving the use of a plurality of spacing elements in the general form of headed rivets, the heads of the rivets being attached to one of the core sections, and a unitary device being provided for locking each of several of the individual rivets against displacement should any of these rivets become detached from the core section.

These and other objects are attained by this invention, the various novel features of which will appear from the description and drawings, disclosing one embodiment of such invention, and will be particularly pointed out in the claims.

In the accompanying drawings:

Figure 1 is a radial sectional view through a portion of a core of a dynamo-electric machine embodying features of this invention, the section being taken along the line I—I of Fig. 2.

Fig. 2 is a broken sectional view through the core of Fig. 1, showing the manner in which the spacing devices and the locking means therefor are arranged in position relative to the end lamination of a core section, the section being taken along the line II—II of Fig. 1.

Fig. 3 is an enlarged fragmentary sec-

tional view showing the manner of securing a group of spacing devices and the locking strip therefor in position relative to a core lamination, along with apparatus, conventionally shown, for securing the parts in operative position.

Fig. 4 is a view similar to Fig. 3 showing a modified construction.

In the embodiment of the invention illustrated, a core 10 of the rotatable element of a dynamo-electric machine is shown mounted on a spider or other support 11. The core is divided into a plurality of spaced sections or groups of laminations, the opposing end laminations of two adjacent core sections or groups of laminations being designated as 12 and 13, respectively, and the space between such groups being designated as 14.

This space 14 between the core sections or groups of laminations is provided during the assembling of the core on the spider 11, spacing devices 15 between the end laminations 12 and 13 serving to space the sections the required distance apart and to effectively maintain the sections in such spaced relation. As shown, these spacing devices 15 are in the form of ordinary iron or soft tinner's rivets comprising a shank portion 16 and an enlarged head 17 which is attached to the lamination 13 with the shank portion extending axially of the machine. These rivets or spacing devices are attached to the lamination 13 preferably before the same is assembled on the spider, the preferable manner of attaching the same being by an autogenous union, as by electrically welding the head portion of the rivet to the lamination, the weld or area of attachment of the rivet being preferably at a plurality of points symmetrically arranged about, or along an annular surface radially outside of, the shank portion of the rivet, this welded area being generally indicated by the character 18 in Figs. 3 and 4. The preferable method of attaching the rivets includes the use of a hollow electrode, such as is shown at 21 in Fig. 3, which may fit over the shank portion of the rivet and a second electrode 23 adapted to bear against the rear side of the lamination 13.

While a proper welded union of the desired strength is readily attainable under normal conditions, it is possible that there may be an imperfect union between one or more of the rivets and the lamination. Hence, where there are no means to prevent it, it might happen that a rivet which had accidentally become detached from the lamination might drop into the air gap, or, if on the rotor, might be thrown into the air gap.

In accordance with this invention, a locking strip 25 of comparatively light material is so arranged relative to a plurality of the

spacing elements and the lamination with which they are associated, as to prevent movement of any one or more of such spacing elements should the same become detached from the lamination. This locking strip 25 is provided with openings 26 which receive the shank portions of a plurality of alined spacing rivets. the body portion of the strip abutting against the inner side of the head 17 of each of the rivets and being secured thereto preferably through an electric weld which may be secured in substantially the same manner as is the weld between the rivet and the lamination. The welded area of the locking strip 25 and the head of the rivet is generally indicated by the designating character 27 in Figs. 3 and 4.

While the safest arrangement includes the attachment of each of the alined spacing rivets to the lamination 13 and the attachment of the locking strip 25 to each of the rivets, with the shank portion of each rivet extending through an opening in the locking strip as indicated in Fig. 3, nevertheless, it will be apparent that satisfactory results, under certain circumstances, may be secured through the attachment of less than the full number of rivets to the lamination or to the locking strip.

In Fig. 4 there is shown a modification of the locking strip 25 and the means for securing the same and the several spacing rivets in operative position. The locking strip, here designated as 28, instead of being a plain flat strip, as in the case of Figs. 1 and 3, has portions bent from the plane of the inner faces of the heads of the rivets and into engagement with the lamination 13, these bent-in portions, designated as 29, being preferably attached to the lamination 13, as by spot-welding, as indicated at 31, this attachment serving as an additional means for retaining the locking strip and holding the individual spacing rivets in operative position. As in the previous case, the shank portions of the rivets extend through openings in the locking strip 28. While maximum security is present when each of the spacing rivets is attached to the lamination 13 and the locking strip 28, and the latter is attached to the lamination 13 between adjacent rivets, nevertheless, it will be apparent that satisfactory results, under certain circumstances, may be secured when only a portion of the rivets are secured to the lamination 13 and the locking strip 28; and, further, it might be possible to satisfactorily secure the spacing rivets in operative position merely by passing the shank portions thereof through the perforations in the locking strip 28, independently of whether or not the rivets are attached to the locking strip or the lamination, and securing the locking strip to the lamination. The locking strip is preferably of ap-

proximately the same width as the head of a rivet and may be mounted in operative position relative to the rivets and the lamination with which it is associated in the 5 manner described above, or in other ways. For instance, the perforations in the locking strip may be slightly smaller than the shank portions of the rivets so that when the latter are pressed into the perforations, they are 10 held quite firmly in position. With this latter arrangement, the rivets may be held in operative position in the core in a satisfactory manner merely by attaching the locking strip to the end lamination or by 15 attaching one or more of the rivets to the lamination, or by both methods of attachment. In any case, where the rivets are to be attached to the locking strip, they may be so attached before the locking strip and rivets 20 are assembled in position in the core. Again, where the rivets are attached to both the lamination and the locking strip, as may be the case with the constructions of both Figs. 3 and 4, the rivet may be welded to both 25 of these parts at a single operation, with the welding electrodes arranged as generally shown in Fig. 3.

The number and relative arrangement of the rivets or spacing devices may be anything desired to provide for the proper 30 mechanical strength to resist compression between the spaced sections, but an arrangement wherein several of the spacing devices are in alinement, as generally indicated in 35 Fig. 2, is preferred for the reason that a comparatively simple form of locking strip may be used to accomplish the desired results.

By using a locking strip of the character 40 described and associated with the core laminations and spacing devices attached thereto in the manner described, an exceptionally simple and cheap spacing means is provided wherein the required mechanical strength is 45 present and accidental detachment of one or more of the individual spacing elements has no serious consequences.

It should be understood that it is not desired that the invention claimed be limited 50 to the exact details of construction shown and described, for obvious modifications will appear to a person skilled in the art.

It is claimed and desired to secure by Letters Patent:

55 1. In a core for electrical apparatus, a lamination, a plurality of separated spacing devices at least one of which is attached to said lamination, and a locking element for said spacing devices comprising a strip having perforations through which said spacing devices extend.

60 2. In a core for electrical apparatus, a lamination, a plurality of spacing devices in contact with said lamination, and a locking 65 element for said spacing devices comprising

a strip having perforations through which said spacing devices extend, said locking element being fastened at one or more points to said lamination.

3. In a core for electrical apparatus, a 70 lamination, a plurality of separated spacing devices associated with said lamination, and a locking element for said spacing devices held against movement relative to said lamination and comprising a strip having perforations through which said spacing devices extend, said locking element preventing movement of a detached one of said spacing devices relative to another of said spacing devices and said lamination. 75 80

4. In a core for electrical apparatus, a lamination, a plurality of separated spacing devices attached to said lamination, and a locking element for said spacing devices attached to said lamination and having perforations through which said spacing devices extend, said locking element being attached to certain of said spacing devices and preventing movement of a detached one of said spacing devices relative to another of 85 90 said spacing devices and said lamination.

5. In a core for electrical apparatus, a lamination, a plurality of spacing devices secured thereto, each of said spacing devices being in the form of a rivet having a shank 95 portion and an enlarged head at one end of said shank portion, and a locking element associated with said spacing devices and held against movement relative to said lamination, said locking element preventing 100 movement of a detached one of said spacing devices relative to another of said spacing devices and said lamination.

6. In a core for electrical apparatus, a lamination, a plurality of spacing devices secured thereto, each of said spacing devices being in the form of a rivet having a shank portion and an enlarged head at one end of said shank portion, and a locking element 105 comprising a strip having perforations receiving the shank portions and attached to the heads of said spacing devices, said locking element preventing movement of a detached one of said spacing devices relative to the other spacing devices and said lamination. 110 115

7. In a core for electrical apparatus, a lamination, a plurality of spacing devices secured thereto, each of said spacing devices being in the form of a rivet having a shank 120 portion and an enlarged head at one end of said shank portion, and a locking element comprising a strip attached to said lamination and having perforations receiving the shank portion and attached to the heads of 125 said spacing devices, the heads of said rivets being united to said locking element by fusion of metal of the parts, and said locking element preventing movement of a detached one of said spacing devices relative to the 130

other of said spacing devices and said lamination.

8. In a core for electrical apparatus, a plurality of axially spaced and laminated sections, means for holding said sections in spaced relation, said means comprising a plurality of spacing elements, each of said spacing elements including a shank portion and an enlarged head bearing against and attached to an end lamination of one of said sections, and a locking element associated with one of said spacing devices and held against movement relative to said lamination, said locking element preventing movement of said spacing device relative to said lamination.

9. In a core for electrical apparatus, a plurality of axially spaced sections or groups of laminations, means for holding said sections in spaced relation, said means comprising a plurality of spacing elements, each of said spacing elements including a shank portion and an enlarged head bearing against and attached to an end lamination of one of said sections, and a locking element having perforations receiving the shank portions and attached to the heads of said spacing devices, said locking element preventing movement of a detached one of said spacing devices relative to the other of said spacing devices and said lamination.

10. In a core for electrical apparatus, a plurality of axially spaced sections or groups of laminations, means for holding said sections in spaced relation, said means comprising a plurality of spacing elements, each of said spacing elements being in the form of a rivet having a shank portion and an enlarged head bearing against and attached to an end lamination of one of said sections, and a locking element comprising

a strip attached to said lamination and having perforations receiving the shank portions and attached to the heads of said rivets, said locking element preventing movement of a detached one of said spacing devices relative to the other of said spacing devices and said lamination.

11. In a core for electrical apparatus, a plurality of axially spaced laminated sections, means for holding said sections in spaced relation and comprising a plurality of spacing elements, each of said spacing elements being in the form of a rivet having a shank portion and an enlarged head, said enlarged head bearing against and being attached to an end lamination of one of said sections, and a locking element comprising a strip having perforations receiving said shank portions and attached to the heads of said rivets, the attachment of said rivets to said locking strip and said lamination being through an autogenous union of the parts, and the points of attachment of the head of a rivet to said lamination and said locking element being in alinement in the direction of the axis of said rivet.

12. As an article of manufacture a spacing element for sections or groups of laminations comprising a perforated metallic strip with a plurality of unitary spacing devices extending through the perforations.

13. As an article of manufacture a spacing element for sections or groups of laminations comprising a perforated strip and a plurality of rivets extending through the perforations, said rivets having a shank portion and an enlarged head.

In testimony whereof, the signature of the inventor is affixed hereto.

EDGAR C. GEORGE.
